UNITED STATES PATENT OFFICE

LOUIS D. DAVIS, OF PHILADELPHIA, PENNSYLVANIA

STENCIL SHEET AND PROCESS OF APPLYING SAME TO WORKABLE SURFACES

Application filed July 26, 1928. Serial No. 295,474.

This invention relates to a stencil sheet for use in producing figures in the surface of solid bodies by the well known "sand blast" method.

5 This method involves the use of a well known rebuffing composition comprising usually a mixture of glue and glycerine which is soluble in water.

Prior to my invention this rebuffing composition, reduced to a plastic state, was manually spread as evenly as possible on the surface of the article to be insculptured, and the article thereafter set aside to permit the composition to become sufficiently hard to 15 permit sketching of the figure to be produced, on the surface of the composition.

After the composition assumed the requisite degree of solidification to permit of the said sketching on the surface thereof of the figure, to be produced on the surface of the 20 article, was sketched on the surface of the composition and the outline of the sketched figure cut through the composition to the underlying surface of the article, after which 25 the portion of the layer of composition lying with the cut outline of the figure was removed, exposing the portion of surface of the article which was to be insculptured by the "sand blast" method.

30 The layer of composition surrounding the figure functions as a stencil to prevent the covered portion of the surface of the article from being affected by the sand used in carrying out the sand blast method.

35 The composition being more or less of a hydroscopic nature required considerable time to assume the proper state of solidity to permit of the sketching of the figure thereon, depending on atmospheric conditions to 40 which it was exposed.

Another disadvantage of the method of spreading the composition on the surface to be insculptured is that it is extremely difficult and almost impossible to produce manually 45 a layer of the composition having a uniform thickness throughout, which causes the composition to dry out unevenly and is, therefore, difficult to sketch upon and to cut.

The principal object of my invention is to 50 provide the composition in a sheet form of

uniform thickness throughout and to provide a suitable backing on one side of the sheet of composition which will be sufficiently tough to permit of the handling of the sheet, and which may be readily peeled off or otherwise removed from the composition when the same has been applied to the surface to be insculptured.

55 My invention also resides in the method employed in placing a uniform layer of composition on the surface to be insculptured, which comprises the use of a web of tough paper, such as parchment or a suitable fabric which will not disintegrate when saturated with water, coating the web with a layer of 60 the composition of uniform thickness throughout while the composition is in a plastic state, drying the composite sheet, subsequently moistening the exposed surface of 65 the composition which softens this face of the 70 composition sufficiently to cause it to adhere to the surface to be insculptured, applying the sheet to the said surface to be insculptured, moistening the backing sheet either before 75 or subsequent to the application of the sheet 80 to said surface to be insculptured which causes the surface of the composition adjacent the backing sheet to become moistened to reduce the effective adhesion between the 85 backing sheet and the composition to such an extent that the backing sheet may be readily peeled off the composition without disturbing the state of adhesion of the composition relative to the surface to be insculptured.

85 Referring to the drawings:

Fig. 1 is a perspective view of a stencil sheet made in accordance with the principles of my invention; and

90 Fig. 2 is a perspective view of the stencil sheet applied to a surface to be insculptured, showing the backing sheet as being partially removed from the sheet of composition.

95 In the drawings, the stencil sheet 1 is shown as comprising a suitable backing sheet 2, having on one of its sides a coating or sheet 3 of a suitable rebuffing composition. X is an article such as a body of stone, etc., having a surface α which is to be insculptured.

100 The component ingredients of the rebuff-

ing composition are well known, usually consisting of a mixture of glue and glycerine in suitable proportions. Substitution of a well known substance of analogous nature to and for either one or both of the said substances 5 may be made without departing from the essential features of the invention.

The points of importance in connection with the rebuffing composition as far as this 10 invention is concerned are that the composition be soluble in water, and that the said composition shall have the requisite ability to withstand or rebuff the assaults of the sand blast.

As this composition in various forms and 15 composed of various ingredients is well known to the art, and forms no part of the present invention, no claim is made thereto.

The backing sheet 2, according to the principles of my invention, is preferably composed of what is generally known as parchment paper, a paper which, when subjected 20 to or saturated with water, will not disintegrate.

Parchment paper, as is well known, can be 25 freely handled when wet without fear of disintegration. Other papers or fabrics of an analogous nature may be employed without departing from the essential features of the 30 invention.

The hydro-soluble rebuffing composition 35 for the best practical purposes is preferably applied to the hydroscopic backing sheet by any well known mechanical device capable of producing a coating of uniform thickness throughout, on the one surface of the backing sheet.

The rebuffing compound being applied to 40 the backing sheet while in a plastic state adheres to the backing sheet and is subsequently dried.

The stencil sheet, before being applied to 45 the surface to be insculptured, is preferably submerged momentarily in water to soften the exposed surface of the rebuffing compound in order that it will readily adhere to the surface to which the stencil sheet is applied.

The stencil sheet is then placed on the 50 surface to be insculptured with the moistened exposed side of the rebuffing compound adjacent thereto.

The momentary submerging of the stencil sheet permits sufficient of the water to penetrate 55 the backing sheet to loosen the rebuffing composition sufficiently to permit the backing sheet to be readily peeled off the rebuffing composition without loosening the rebuffing sheet from the surface to be insculptured, to which it has been applied.

While I prefer to submerge the sheet, as 60 above noted, the exposed side of the rebuffing compound may be moistened before being applied to the article and the exposed face of 65 stencil sheet has been applied, rolled, or

the backing sheet may be moistened after the otherwise treated to flatten the stencil sheet on the surface to be insculptured.

After the stencil sheet has been applied and the backing sheet removed, the rebuffing compound is ready for immediate use, as the body of the compound has not been affected by the slight amount of water applied for the purpose of causing the compound to adhere to the surface of the article and for loosening 70 the backing sheet.

After the insculpturing of the surface of the article has been completed, the rebuffing compound which formed the stencil or shield is removed in the usual manner. 75

I claim:

A process for applying a hydro-soluble rebuffing composition to a surface to be insculptured by sand blast, consisting of reducing the compound to a substantially plastic state, applying the compound while in said plastic state to one side of a backing sheet of parchment paper while said compound is in said plastic state whereby said compound adheres to said backing sheet, drying the coated sheet to solidify the compound, subsequently moistening the exposed face of the compound to produce an adhesive condition thereon, applying this adhesive face of the compound to the surface to be insculptured, moistening the backing sheet to reduce the state of adhesion between the sheet and the compound, and finally peeling the backing sheet off the layer of compound. 90
